UNITED STATES PATENT OFFICE.

MAURICE J. KEARNEY, OF BROCKTON, MASSACHUSETTS.

CUSHION-HEEL FOR BOOTS AND SHOES.

No. 866,867.

Specification of Letters Patent.

Patented Sept. 24, 1907.

Application filed April 27, 1906. Serial No. 313,974.

To all whom it may concern:

Be it known that I, MAURICE J. KEARNEY, residing at Brockton, in the county of Plymouth and State of Massachusetts, have invented new and useful Improvements in Cushion-Heels for Boots and Shoes, of which the following is a specification.

My invention relates to improvements in cushion heels for boots and shoes, and has for its object to provide such a heel composed of sections one of which is 10 permanently attached to the boot or shoe and the other of which may be readily attached or detached thereto, the said sections being provided with means whereby the attachment and detachment may be accomplished with facility and without particular skill, and the attachment a secure one without detracting appreciably from the cushion function of the heel.

With these objects in view the invention consists in a cushion heel for boots and shoes constructed as herein-after described and claimed, reference being had to the 20 accompanying drawing, in which—

Figure 1 is a perspective view of the base section of the heel; Fig. 2 similar view of the top or cushion section; Fig. 3 sectional view of the section shown in Fig. 1; Fig. 4 sectional view of the section shown in Fig. 2; Fig. 5 detail of two parts of the heel assembled; Fig. 6 a perspective view of one form of the anchor of the base section; Fig. 7 a perspective of the anchor strip of the top section; Fig. 8 a detail of the anchor of the top section.

30 In the said drawing the reference numeral 1 designates the base or permanent section of the heel. This section is a molded one of any suitable composition such as hard rubber and may be manufactured in various standard sizes and shapes, and, therefore, very economical, as compared with structures made up of leather layers. Incorporated into this base section of the heel in the process of molding the same is an anchor which consists of a single plate 2 conforming in outline to that of the heel section. The anchor is of metal or 35 the equivalent, preferably steel, and is provided with screw-threaded holes 3 marginally disposed with respect to the section 1, which serve for attaching and detaching the cushion heel section as will be described. The body of the section 1 is provided with a series of screw-leading holes 4, registering with the holes 3 in the anchor. The said anchor, and also the body of the heel-base section, is provided with a series of openings 5, 6, for the passage of nails by which the section is permanently secured to the boot or shoe.

50 For the purpose of providing an air cushion in the base-section of the heel, the latter is hollowed out at its middle as shown at 7, and centrally of this hollowed out cavity is an opening 8 extending entirely through said section. The anchor-plate is provided

with a similar central opening 9 defined by a flange 55 10, which fits into and bears against and supports the walls of the cavity 7.

The attachable and detachable top or cushion section 11 of the heel consists of molded soft rubber, and incorporated therewith in the process of molding at 60 the forward end thereof is an anchor strip 12 extending from side to side across the front edge of the heel section, and conforming to the shape thereof, and provided with rearwardly extending members 12^a, 12^b. Said anchor strip forms an extended means of attachment about the fore part of the cushion section 11 of the heel, whereby the latter may be firmly connected to the base section. The said anchor strip is provided with a number of openings 13, registering with similar openings 14 in the cushion section 11 for the passage of 70 screw-shanks. Screws 15 are passed through the openings 14 and 13 into the screw-leading openings 4 in the base section 1, and into threaded engagement with the screw threaded openings 3 in the anchor of said base section, whereby the cushion section of the heel is 75 firmly connected to the base section. The incorporation in the cushion-section 11 of the heel of a metallic or like anchor is essential to its firm connection with the base section, avoiding liability of the screw-shanks either enlarging the bore of the holes in the 80 cushion section of the heel or causing a tearing of said section, in either of which possible events, the cushion section would become loose and wobbly and soon become detached from the base section. At the same time the incorporation of such metallic anchor 85 into the cushion section tends to detract from the cushion function thereof. To reduce this detraction to a minimum, the anchor 12 of my invention may be of strip form, conforming to the marginal shape and dimensions of the fore part of said section, leaving the 90 central portion 16 and substantially the rear portion 17 thereof, where the cushion action is most desired, free of restraint to perform its function.

At the rear I provide a small anchor 18 which is molded into the cushion section 11 and provided with 95 a screw opening 19 through which a screw 20 may be passed into engagement with a corresponding threaded opening 3 in the anchor of the base section. Preferably and for the purpose of providing an anti-slipping plug to increase the frictional hold of the 100 cushion-heel upon the ground, the anchor 18 is provided with a plug opening 21 into which may be driven a wooden or other suitable plug 22. This plug being exposed on the wearing surface of the cushion heel serves efficiently to guard against slipping on frosty 105 or icy streets.

The screw passages or openings 14 in the cushion section of the heel, above the anchor strip therein,

may be frusto-conical, decreasing in area toward the wear surface, and be filled with rubber plugs 23 to prevent the entrance of dirt or foreign matter.

By my invention I provide a cushion heel for boots and shoes of novel and economical manufacture, the cushion section of which may be readily and securely attached to the base section. The cushion section may be easily removed when worn and a new cushion section substituted therefor.

10 What I claim as new and desire to secure by Letters Patent is:—

1. A cushion heel for boots and shoes consisting of a base section provided with a central cavity, and an anchor incorporated therein and provided with screw threaded openings and further provided with a flange extending in said cavity; and a cushion section provided with an anchor having openings corresponding to the screw openings
- 15

in the base section and screws extending through the strip and plate for connecting the sections together.

2. A cushion heel for boots and shoes consisting of a 20 plastic base section provided with a central cavity, an anchor plate embedded in said section and conforming in contour to the contour of the section, said plate having a central opening and a flange extending in said cavity and further provided with screw openings and a cushion section provided with an anchor strip arranged in close proximity to the forward edge of said cushion section and having rearwardly extending arms, said strip having openings corresponding to the openings in said plate, and means extending through the strip and plate for connecting the sections together.
- 25

In testimony whereof I have hereunto set my hand in the presence of two subscribing witnesses.

MAURICE J. KEARNEY.
